INVENTOR

Norris Elmore Clark,

P. J. Flynn ATTORNEY

UNITED STATES PATENT OFFICE.

NORRIS ELMORE CLARK, OF PLAINVILLE, CONNECTICUT.

CORNER-BEAD.

1,257,980.

Specification of Letters Patent.

Patented Mar. 5, 1918.

Application filed July 30, 1913. Serial No. 781,985.

To all whom it may concern:

Be it known that I, NORRIS ELMORE CLARK, a citizen of the United States of America, and residing at Plainville, in the county of 5 Hartford and State of Connecticut, have invented new and useful Improvements in Corner-Beads, of which the following is a specification.

My invention relates particularly to metallic corner beads of the so-called clip type.

One object is to provide a construction which can be manufactured economically. Another object is to provide a construction which is strong and affords a good clench 15 for the plaster or cement. Another object is to provide a construction in which the clips can be readily assembled with the bead proper and adjusted to the desired position and held securely in place.

20 The invention consists of a bead proper with attaching clips, the bead and clips being specially constructed for manufacture and attachment as hereinafter set forth.

Figure 1, is a perspective view of a fragment of a corner bead embodying improvements of my invention, part of the bead proper being broken away to show the construction of a clip.

Fig. 2, is a horizontal section and plan 30 view.

Fig. 3, is a similar view showing the bead applied to a corner and plastered.

Figs. 4 and 5 are side and edge views respectively of one of the clips with its fingers formed but before the clip is bent.

Fig. 6, is a fragmentary perspective view showing a slight modification of one of the clips.

Fig. 7, is a perspective view of a fragment of a clip having a modified form of connecting fingers.

Fig. 8, is a perspective view of a fragment of a clip with another modification of attaching fingers.

45 Fig. 9, is a perspective view of a fragment of a clip with another form of attaching finger.

Fig. 10, is a perspective view of a fragment of another modification of a clip.

50 The bead proper is formed from a strip of metal folded along its middle portion so as to have a rounded front edge or head 11 with outwardly and rearwardly flaring sides 12, 12. Just back of the head, the sides 55 are bent inward toward each other so as to leave a narrow throat 13. Between the

head and the throat is a passage 14 and in rear of the throat is a mouth 15. The extreme rear edges may be curled or flanged outwardly as at 16 to give additional rigidity if desired. The bending in of the sides forms exterior grooves 17, 17 for the plaster with exterior shoulders such as 18 to prevent the plaster from falling out. The interior shoulders such as 19 and the inner 60 walls of the sides 12 afford gripping and bearing surfaces for the clips.

Each clip is preferably formed of a straight strip of metal bent in the middle so as to form arms 20, 20 for attachment 70 to the corner. The angle 21 of the clip is adapted to fit snugly up into the mouth 15 of the bead proper but without extending into the passage 14. The clip is provided with one or more fingers preferably 75 two such as 22, 22 as shown in Figs. 1 to 6 inclusive. These fingers are formed by cutting and bending portions of the edges of the strip at its middle portion as shown in Figs. 4 and 5. The strip is then bent 80 at the center along the line X, X to an acute angle substantially as shown in Fig. 2. This causes the two fingers to extend outward as shown in Figs. 1, 2 and 6. The main portions of the fingers are then in a 85 common vertical plane and the tips 23, 23 extend in opposite directions.

The throat 13 is preferably made just slightly wider than the thickness of the metal of the strip, which provides a minimum opening of the mouth and affords a maximum depth of the shoulder 18 to prevent the chipping out of the plaster. The tips 23, 23 engage in front of the shoulders 19, 19 so as to hold the clip against the bead 90 proper with its angle 21 snugly in the mouth 15. The angle of the mouth 15 between the sides 12, 12 is preferably an acute angle and slightly greater than the angle between the arms 20, 20. The clip is assembled in the bead proper by slipping it into one end of the bead, the tips 23, 23 going into the passage 14, the fingers 22, 22 passing through the center throat 13 and the arms 20 and angle 21 passing into the 105 mouth 15. By bending the arms outward as shown for instance, in Fig. 3 the arms, fingers and tips are all caused to bind against the adjacent walls of the bead proper so that the bead cannot move longitudinally of the clips or vice-versa.

The sides 12, 12 of the bead proper are

preferably made wide enough to extend back over the corner 24 of the support to which the bead is attached, and the sides are preferably provided with openings such as 25 5 for the plaster. The sides may also be provided with smaller holes such as 26 for the plaster or for the use of nails or attaching wires if desired. The arms of the clips are also provided with holes such as 27, 27 for 10 nails or attaching wires.

The clip thus far described may be cheaply made from strips by cutting and forming the fingers as shown in Figs. 4 and 5 by means of suitable dies. The clip may 15 be packed and shipped in this form and may be readily bent into shape for assembling by simply bending it along the line X, X which brings the fingers and tips at exactly the right angle for fitting within the mouth and 20 throat and passage of the bead proper or the clips may be bent into angular form before shipment if desired.

In addition to the frictional engagement 25 for preventing relative longitudinal movement of the clips in the bead, the corner of the clip may be bent out slightly as at 30 in Fig. 1 or as at 31 in Fig. 6 to extend into one of the openings in the side of the bead.

Instead of forming the fingers of the clip 30 from the edges of the strip as previously described, they may be formed from the interior portions as shown at 32, 32 in Fig. 7.

Attachment may also be made by means 35 of a single finger such as 33 with one or more lateral tips such as 34, 34, as shown in Fig. 8.

Another modification is shown in Fig. 9 where the finger 35 is provided with a single tip 36 bent to fit in the passage 14 of the 40 bead proper.

In the form shown in Fig. 10 the arms 37 and 38 are formed by splitting a strip of double width but leaving the two arms attached at 39 which constitutes the finger portion. In this case the tips 40, 40 are bent 45 laterally from the finger portion for fitting in the passage 14 of the bead proper.

In all of these forms it will be noted that

the construction of the finger portion or portions is such that it is only necessary to 50 make the throat 13 of a slightly greater width than the thickness of the metal of which the clip is formed. The clips may be readily assembled but are securely held in 55 position.

What I claim is:—

1. A corner bead comprising, the combination of a strip doubled along its middle portion to form a head with rearwardly and outwardly extending sides bent inwardly toward each other immediately back of the head to form interior and exterior shoulders and a narrow throat, said sides having openings therein, together with a clip formed from a strip bent angularly at its center to 60 fit within said mouth between the inner walls of said sides and provided with a finger extending outwardly from the angular portion of a single thickness of metal and provided with a laterally extending tip portion extending into said passage in front of one of said interior shoulders, said clip having a portion bent slightly outward adjacent 65 said finger for engagement with one of said openings.

2. A corner bead clip blank comprising a strip, the main portion of which is substantially flat and having two fingers at opposite sides of its central portion formed by cutting the strip transversely and longitudinally, 70 said fingers being joined to the body of the strip on the central transverse line and somewhat offset from the main portion and one finger pointing toward one end of the strip and the other finger pointing toward the 75 other end of the strip, whereby the strip is weakest at its central point on a line with the bases of said fingers so that said strip may be bent by hand and the bending will cause the free ends of said fingers to project 80 and form shoulders for holding the clip in connection with a bead.

NORRIS ELMORE CLARK.
